(Cl. D45—19)

To all whom it may concern:

Be it known that I, Norman Shuman, a citizen of the United States, residing at Brooklyn, in the county of Kings and State of New York, have invented a new, original, and ornamental Design for a Pin, of which the following is a specification, reference being had to the accompanying drawing, constituting a part hereof.

Fig. 1 is a perspective view of a pin, showing my new design;

Fig. 2 is a front elevational view;

Fig. 3 is a side elevational view;

Fig. 4 is a rear elevational view.

I claim:

The ornamental design for a pin, substantially as shown.

NORMAN SHUMAN.
